CLAIM

The ornamental design for a sensor bracket for inspection of T-root turbine blades as shown and described.

DESCRIPTION

FIG. 1 is a first perspective view of a sensor bracket for inspection of T-root turbine blades embodying the invention. FIG. 2 is a second perspective view of the sensor bracket for inspection of T-root turbine blades embodying the invention. FIG. 3 is a top view of the sensor bracket for inspection of T-root turbine blades of FIGS. 1 and 2.

FIG. 4 is a bottom view of the sensor bracket for inspection of T-root turbine blades of FIGS. 1 and 2.

FIG. 5 is a front side view of the sensor bracket for inspection of T-root turbine blades of FIGS. 1 and 2.

FIG. 6 is a back side view of the sensor bracket for inspection of T-root turbine blades of FIGS. 1 and 2.

FIG. 7 is a left view of the sensor bracket for inspection of T-root turbine blades of FIGS. 1 and 2.

FIG. 8 is a right view of the sensor bracket for inspection of T-root turbine blades of FIGS. 1 and 2; and,

FIG. 9 is a view in cross section of the sensor bracket for inspection of T-root turbine blades of FIG. 5 through cut plane 9.

The elements shown in broken lines are included for the purpose of illustrating environment and form no part of the claimed design.
